PHILIPPE DE CLAMECY, OF BOSTON, MASSACHUSETTS, ASSIGNOR TO CORONA TYPE-WRITER COMPANY, INC., OF GROTON, NEW YORK, A CORPORATION OF NEW YORK.

COLLAPSIBLE TYPEWRITING-MACHINE.

1,355,818.

Specification of Letters Patent. Patented Oct. 19, 1920.

Application filed January 26, 1918. Serial No. 214,017.

To all whom it may concern:

Be it known that I, PHILIPPE DE CLAMECY, a citizen of the United States, and resident of Boston, county of Suffolk, and State of Massachusetts, have invented certain new and useful Improvements in Collapsible Typewriting Machines, of which the following is a specification.

This invention relates to improvements in typewriting machines and more particularly to typewriting machines adapted to be collapsed or folded to make the machine compact and readily portable.

The invention has for one of its objects the provision of a typewriting machine in which the platen and keyboard are movable relatively to the printing instrumentalities from their normal operative positions into more compact relation with each other and the printing instrumentalities.

Another object of the invention is to provide a visible typewriting machine having upwardly and rearwardly movable type-bars, a universal keyboard slidable rearwardly beneath the type-bars, and collapsible means forming constantly maintained mechanical operating connections between the keys and the devices operated thereby.

A further important object of the invention is to provide a typewriting machine having a platen carriage and vertically extensible and collapsible means mounted on the carriage for supporting the platen, whereby the platen may be moved from a normal elevated position above the carriage downwardly to a lower and more compact position above the carriage and out of operative relation with the type-bars.

A further important object of the invention is to provide a visible typewriting machine having a ribbon holder and platen and collapsible devices for supporting the platen and ribbon holder.

Another object of the invention is to provide a typewriting machine in which the platen carriage is provided with collapsible platen supporting means and the carriage bed is provided with collapsible means for holding the ribbon in co-operative relation with the platen.

A further object of the invention is to provide a collapsible visible typewriting machine having upwardly and rearwardly swinging type-bars supported on one frame part, a keyboard frame part slidable from an

extended position to a more compact position beneath the type-bars, a plurality of banks of keys mounted on vertically slidable stems supported on the keyboard frame part fixed distances apart, and collapsible oscillatory means constantly connected with the key stems and type-bars and adapted, when oscillated by depressing the keys, to actuate the type-bars.

Another object of the invention is to provide a light and inexpensive collapsible typewriting machine in which the mechanism is supported on a box-like frame adapted to completely inclose the mechanism when the machine is collapsed, said box-like frame having hinged sections adapted when opened to permit the parts of the machine to be extended into co-operative relation.

A further object is to provide a collapsible typewriting machine having a box-like main frame part adapted to completely inclose the mechanism when the machine is collapsed, and a keyboard frame part slidable within the box-like frame part, the box-like frame part having a hinged front wall adapted to support the keyboard frame part when the keyboard is in its extended operative position.

In the drawings, Figure 1 is a side elevation of the machine with the parts in their extended or normal operative positions;

Fig. 2 a side elevation showing the machine collapsed;

Fig. 3 a plan view of the machine in extended condition;

Fig. 4 a vertical sectional view taken centrally of the machine with the parts in the positions shown in Figs. 1 and 3;

Fig. 5 a view similar to Fig. 4 with the parts in the positions occupied thereby when the machine is collapsed;

Fig. 6 a fragmentary horizontal sectional plan showing the collapsible operating connections between the keys and the parts controlled by the keys;

Fig. 7 a front elevation of the machine in extended condition;

Fig. 8 a detail view showing a part of the key action; and

Fig. 9 a detail view showing part of the platen shift mechanism.

Referring to the drawings by numerals, the frame of the machine comprises a box-like inclosing casing having a rigid main portion formed with a bottom 1, a rear wall 110

2, and side walls 3. A plate or casing section 4 is hinged at 5 to each of the side walls 3, and a front wall section 6 is hinged at 7 to the forward edge of the bottom 1 of the 5 main portion of the combined casing and frame. A cover or upper portion of the casing is hinged at 9 to the upper edge of the rear wall 2 and is preferably formed of a plurality of hinged sections 10, 11, 12 and 10 13. The hinged front wall section 6 is provided with a pair of rubber feet 14 adjacent its forward edge and the bottom 1 of the rigid main section of the frame is provided with a rubber foot 15 adjacent each corner 15 thereof. The upper edges of the side walls 3 of the main section of the frame are connected by a transversely extending plate 16 which is depressed intermediate its ends at 17 to receive the type basket, and said walls 20 3 are also connected by a finishing plate 18 which extends between said walls at the front edges thereof.

A keyboard frame part 19, preferably formed with integral top, bottom, side, and 25 front walls, and having an open rear end, is slidably held to the main frame part to move forwardly and rearwardly out of and into said main frame part. The keyboard frame part 19 is supported on the hinged front section 6 of the inclosing case or main frame when in its normal extended position, and is held to the main frame part by ribs 20 formed on the sides of the keyboard frame part and slidably engaging in grooves 21 30 formed on the inner surfaces of the side walls 3 of the main frame part. The extent of the sliding movement of the keyboard frame 19 is limited by thumb-screws 22 extending through apertures in the side walls 40 3 of the main frame and through elongated slots 23 in the side walls of the keyboard frame. By loosening the screws 22 the keyboard frame may be moved into or out of the main frame, and may be locked in its 45 adjusted position by tightening said screws.

A plurality of rows or banks of keys, forming a universal or standard keyboard, are mounted on the keyboard frame part 19 to move therewith, and the banks of keys 50 are held spaced a fixed distance apart at all times. Each type-bar operating key 24 is rigidly held on the upper end of a vertically reciprocable key stem or rod 25 extending through the top wall of the keyboard frame 55 19 and slidably guided in a tube or sleeve 26 rigidly held at its lower end to said top wall of the keyboard frame. Each of the stems 25 and sleeves 26 supporting a bank of keys are of the same length, but the stems and 60 sleeves of the several banks are of different lengths to support the rows or banks of keys in different horizontal planes. The extent of depression of the keys is limited by the 65 engagement of the keys with the upper ends of the sleeves 26, and the upward movement

of the keys is limited by collars 27 formed on the stems 25 and normally engaging the under side of the top wall of the keyboard frame 19.

Each of the stems 25 is operatively connected to rotate a jointed and collapsible rock shaft 28, there being a shaft 28 for each key stem 25. Any suitable operating connections between the stems 25 and shafts 28 may be provided. As shown, each stem 25 70 is provided with a horizontally extending arm or projection 29 working in an elongated slot 30 in the outer end of a rock arm 31 fixed on the forward end of the rock shaft 28. Each shaft 28 is formed with a forward 75 section journaled in a bearing formed in a post 32 held to the bottom of the keyboard frame 19, and is also journaled in one of a series of apertures in an upstanding rib or flange 33 formed on the bottom of the keyboard frame. Each shaft 28 is formed with an intermediate section 34 extending through one of a series of apertures or bearings formed in an upstanding rib 35 carried by a slide 36, and a rear section 37 extending 80 through and journaled in one of a series of apertures or bearings in an upstanding rib 38 rigidly held to the bottom 1 of the main frame part. The slide 36 extends transversely of the machine and the ends 85 thereof slidably engage in the lower grooves 21 formed in the side walls 3 of the main frame. The intermediate section 34 of each shaft 28 is shiftable forwardly and rearwardly with the slide 36 and is connected 90 with the front section of the shaft by a knuckle jointed shaft section 39. The knuckle jointed shaft section 39 is pivotally connected at its forward end with the rear end of the forward shaft section by a horizontal pivot pin 40 and is similarly connected 95 at its rear end by a horizontal pivot pin 41 with the forward end of the intermediate longitudinally shiftable shaft section 34. The rear end of shaft section 34 is connected with 100 the forward end of the shaft section 37 by a knuckle jointed shaft section 42 similar to the jointed section 39. The section 42 is held to the sections 34 and 37 by horizontal pivot pins 43 and 44, and the knuckle joints 45 105 and 46 of the shaft sections 39 and 42 are preferably constructed as shown so that the pivotal points thereof are held out of alignment with the shaft bearings. As a further means for preventing the knuckle joints 110 from being shifted into alignment with the shaft bearings when the shaft is extended, the parts of the shaft are formed of such length that the screws 22 will engage the rear end of slots 23 in the keyboard frame 115 19 and stop the outward movement of said frame before the shaft 28 has been extended sufficiently to bring the pivotal points of the knuckle joints in alignment with the shaft.

A drum 47 is fixed on each of the rear 120

sections 37 of shafts 28 to rotate therewith when its associated printing key 24 is depressed. Flexible wires or cords 48 are secured at their lower ends to the drums 47 5 to wind thereon, and the upper ends of said cords are secured to rearwardly extending arms or projections 49 formed on the type bars 50. Each type bar 50 is pivotally mounted adjacent its rear end on a 10 curved rod or type-bar-hanger 51, rigidly held at its ends to the transversely extending frame plate 16 at opposite sides of the depressed portion 17 of said plate. The segmental basket of type bars is normally 15 supported in a horizontal position within the depression 17 formed in the plate 16, the heads of the type bars 50 being normally supported on a curved type bar rest 52. Suitable springs 53 may be provided 20 for normally forcing the type bars rearwardly and downwardly, and suitable springs 54 are provided for normally holding the rock arms 31 and key stems 25 in raised position. It will be obvious that, 25 upon the depression of one of the printing keys 24, its coöperating jointed shaft 28 and drum 47 will be rotated, winding cord 48 on said drum, and causing the associated type bar to swing upwardly and rearwardly 30 to the printing point.

A platen carriage 55 is supported adjacent the rear end of the main frame part above and at the rear of the type bars 50, and is adapted to travel transversely of said 35 frame part on a carriage bed 56. The carriage bed 56 is fixed adjacent its ends to the upper ends of a pair of vertical slides 57 of dovetail form, slidably held in vertically extending undercut grooves or ways 40 58 formed in the side walls 3 of the main frame part. The lower ends of the slides 57 normally rest at the lower ends of the ways 58, as shown in Figs. 4 and 5, to support the carriage bed in its normal position. 45

The carriage 55 is provided at each end thereof with means for rotatably supporting a platen 59. As shown, the carriage and bed are normally supported in close 50 proximity to the type bar hanger 51, and means is provided for normally supporting the platen in an elevated position above the carriage in coöperative relation with the type, said platen-supporting means being 55 collapsible to permit the platen to be lowered into close proximity with the carriage and out of coöperative relation with the type to reduce the height of the machine when not in use. I prefer to employ for this 60 purpose the vertically collapsible supporting mechanism shown in the drawings.

The collapsible supports at each end of the carriage are constructed in the same manner and each comprises a pair of 65 knuckle jointed arms 60 and 61 in the upper

ends of which one end of the platen shaft 62 is journaled. The arms 60 and 61 are spaced apart at their lower ends, the lower end of arm 60 being pivotally held on a horizontal pivot pin 63 in a recess 64 in the 70 carriage 55 adjacent the forward edge of the carriage, and arm 61 being held in a recess 65 adjacent the rear edge of the carriage on a horizontal pivot pin 66. The arm 60 is provided with a forwardly breaking 75 knuckle joint 67, and arm 61 is provided with a rearwardly breaking knuckle joint 68. The sections of the arms 60 and 61 are normally held in alinement by a pair of links 69 and 70, pivotally held 80 at their lower ends on the shank of a locking screw 71 working in a vertical slot 72 in an upstanding plate or bracket 73 which is rigidly held to the end of the carriage 55. The upper end of link 69 is pivotally held to the pivot pin of the knuckle joint 67 of arm 60, and the upper end of link 70 is pivotally held to the pivot pin of the knuckle joint 68 of arm 61.

Any suitable means may be provided for 90 rotating the platen for line spacing, such as a line-space lever 74, pivotally held to the platen shaft 62, and carrying a dog 75 adapted to engage a ratchet wheel 76 fixed to the platen 59 at one end thereof in the 95 usual manner. Any suitable carriage escapement mechanism, and other usual mechanisms or devices commonly applied to typewriting machines may be provided, such devices not being shown as they form no 100 part of the present invention. Any suitable form of paper guiding and feeding means may be provided. I have shown a feed roll 77 rotatably supported at its ends in the lower ends of a pair of arms 78 fixed at 105 their upper ends on square bosses 79 formed on the upper ends of arms 61. The usual thumb wheels 80 may be provided for rotating the platen.

The ribbon 81 is wound in the usual manner on two spools 82 mounted on shafts 83 supported on the transversely extending frame plate 16. Any suitable mechanism may be employed for rotating the spools 82 to feed the ribbon lengthwise, and any desired means may be provided for vibrating the ribbon to cover and uncover the printing point. The ribbon is supported adjacent the printing point by a vertically collapsible ribbon holder having a ribbon guide 110 115 84 of substantially U-shape, the upwardly extending arms of which are forked to receive the ribbon and permit lengthwise and vertical movement of the ribbon relatively to the holder. The U-shaped portion 84 of the ribbon holder is mounted on a collapsible support constructed in substantially the same manner as the collapsible platen supporting means heretofore described. This 120 collapsible support comprises a plate or 125 130

bracket 85, held to the front edge of the carriage bed 56 by suitable screws 86, and provided with a vertical slot 87 through which the shank of a locking screw 88 extends. A pair of knuckle-jointed arms 89 and 90 are pivotally held by a pin 91 to a lug depending from the bottom or transversely extending member of the U-shaped ribbon guide 84, and are held to the plate 85 at their lower ends by pivot pins 92 and 93, respectively. A pair of links 94 and 95 are pivotally held at their lower ends on the shank of the locking screw 88. The upper end of link 94 is pivotally held to the pivot pin of the outwardly breaking knuckle joint 96 of arm 89, and the upper end of link 95 is pivotally held to the pivot pin of the outwardly breaking knuckle joint 97 of arm 90. Arm 90 is provided at its upper end with a stop or lug 98 and arm 89 is provided with a similar stop 99, said stops being adapted to engage under the ribbon guide 84 at opposite sides of the pivot pin 91 when the ribbon holder is extended to prevent rocking 25 of the guide portion 84 of the ribbon holder.

The head of each of the type bars 50 is preferably provided with three type, as shown, and means is provided for imparting a double case shift movement to the platen. The middle case shift keys 100, one of which is provided at each side of the keyboard, are supported on vertically reciprocable key stems 101 similar to the key stems 25, and operatively connected to rotate the 30 jointed and collapsible rock shafts 102 through rock arms 103. The rock arms 103 and rock shafts 102 are constructed and mounted in the same manner as the type-bar-operating shafts 28. Rock arms 103 are held to the rear ends of the shafts 102 and the outer ends of said rock arms are pivotally connected at 104 with the lower ends of links 105, the upper ends of which are forked as shown at 106. The upper case 40 shift keys 107 located at each side of the keyboard are mounted on reciprocable key stems 108 connected with rock arms 109 to rotate the jointed and collapsible rock shafts 110. Rock arms 111 are held to the rear 45 ends of the shafts 110 and are pivotally connected at 112 with the lower ends of links 113 the upper ends of which are forked as shown at 114. The slides 57 upon which the carriage bed 56 is supported, are connected at their lower ends by a transversely extending rod 115 which extends through the forked upper ends 106 and 114 of the links 105 and 113. The rod 115 is formed with angular enlarged portions 115a extending through the forked ends 106 and 114 of the links 105 and 113, and pins 125 and 126 extend through said angular portions and engage in slots 127 and 128 formed in the forked ends of said links and serve to normally hold the links in the position shown

in Figs. 4, 5 and 9. The rock arm 111 is longer than the rock arm 129 to adapt a greater vertical movement to be imparted to the platen by the shift keys 107 than that imparted to the platen by the shift keys 100. 70

The space bar 116 is supported on vertically reciprocable stems 117 passing through tubular sleeves or guides 118 held to the keyboard frame part 19. Each stem 117 is provided with an offset portion 119 working 75 in the slotted upper end of a rock arm 120 held to the forward end of a jointed and collapsible rock shaft 121. The rock shafts 121 are constructed and mounted in the same manner as the rock shafts 28 and have 80 drums 122 fixed to the rear ends thereof. Cords 123 are secured to the drums 122 to wind thereon and may be operatively connected in any suitable manner to actuate a carriage escapement mechanism when the 85 space bar is depressed.

When it is desired to collapse the machine the platen 59 may be lowered into close relation with the carriage 55 by loosening the clamping screws 71 and moving said screws 90 upwardly in the slots 72 in brackets 73, thus forcing the upper ends of the links 69 and 70 away from each other, breaking the knuckle joints 67 and 68 of the arms 60 and 61 and lowering the platen 59, together with 95 the feed roller 77 and the line spacing lever 74, from the positions shown in Figs. 1, 3, 4, and 7 to the positions shown in Figs. 2 and 5, and materially reducing the height of the machine. The ribbon holder 84 may be lowered by loosening the clamping screw 88 and moving the same upwardly in the slot 87 in the plate 85, thus forcing the upper ends of the links 94 and 95 away from each other, breaking the knuckle joints 96 and 97 of 100 the arms 89 and 90, and lowering the holder 84 into closer relation with the carriage bed 56 at a point in front of the platen 59, as shown in Figs. 2 and 5.

The length of the machine from front to 110 rear may be materially reduced by loosening the locking screws 22 and sliding the keyboard frame part 19 rearwardly within the main frame part beneath the type basket, thus moving the keyboard into closer relation with the type bars and the platen. It will be obvious that when the keyboard frame part 19 is slid rearwardly in the guide-ways 21 in the side walls 3 of the main frame part the knuckle joints of the 115 collapsible rock shafts will break upwardly permitting the front sections of said shafts to move rearwardly until the pivot points 40 are in close relation with the pivot points 41 of the intermediate sections 34, and that 120 the slide 36 will then be moved rearwardly, carrying with it the intermediate sections 34 of the collapsible shafts, until the pivot points 43 are in close relation with the pivot points 44 of the rear sections 37, as shown 125 130

in Fig. 5. It will thus be seen that the entire keyboard may be moved within the main frame part beneath the type basket without breaking the mechanical connections between the keys and the type bars, or the connections between the shift keys or the space bar and the mechanisms operated thereby. When the several mechanisms have been moved into compact relation with each other, as above described, the hinged section 6 of the box-like frame or casing may be swung upwardly in front of the keyboard, the side plates 4 may be swung upwardly about their hinges 5, and the jointed cover portion comprising the hinged sections 10, 11, 12 and 13 may be folded, as shown in Figs. 2 and 5, to inclose the upper portion of the machine. As shown in Fig. 2, the sections of the jointed cover portion rest upon the edges of the hinged side plates 4 and are supported thereby. Any suitable means may be provided for fastening the hinged sections in closed position, and any suitable means may be provided for supporting the sections of the jointed cover portion when the machine is extended. The hinged side plates 4 are provided with suitable recesses 124, into which the heads of the locking screws 71 may pass when the side plates 4 are swung upwardly to closed position.

What I claim is:

1. In a collapsible typewriting machine, the combination of a key action, type-bars, a platen carriage, a platen, and collapsible means mounted on the carriage for supporting the platen.

2. In a collapsible typewriting machine, the combination of a key action, type-bars, a platen carriage, a platen, and means mounted adjacent each end of the carriage for rotatably supporting the platen, said means being collapsible to permit lowering of the platen to reduce the height of the machine when not in use.

3. In a collapsible typewriting machine, the combination of a key action, type-bars, a platen carriage, a platen, and means mounted on the carriage for normally supporting the platen in an elevated position above the carriage in coöperative relation with the type-bars, said means being operable to shift the platen to a lower position above the carriage and out of coöperative relation with the type-bars.

4. In a collapsible typewriting machine, the combination of a key action, type-bars, a platen carriage, a platen, and means mounted adjacent each end of the carriage for rotatably supporting the platen in an elevated operative position relatively to the type-bars, said means being operable to shift the platen to a lower inoperative position relatively to the type-bars.

5. In a collapsible typewriting machine,

the combination of a key action, type-bars, a platen carriage, a platen, and means mounted adjacent each end of the carriage for rotatably supporting the platen, said means being operable to lower the platen vertically to an inoperative position relatively to the type-bars and in closer relation with the platen carriage.

6. In a collapsible visible typewriting machine, the combination of a key action, upwardly and rearwardly movable type-bars operable by the key action, a platen carriage, a carriage bed supported at the rear of the type-bars, a platen, collapsible means mounted on the carriage for normally supporting the platen in an elevated position in coöperative relation with the type-bars, ribbon spools, and a collapsible ribbon holder mounted on the carriage bed.

7. In a collapsible visible typewriting machine, the combination of a key action, upwardly and rearwardly movable type-bars operable by the key action, a platen carriage, a support for the carriage, collapsible means carried by the carriage for normally supporting the platen in an elevated position in coöperative relation with the type-bars and operable to permit lowering of the platen to a more compact inoperative position, and a collapsible ribbon holder adapted to normally support the ribbon adjacent the printing point.

8. In a collapsible typewriting machine, the combination with the key action and type-bars, of a platen carriage, and a ribbon guide and a platen both shiftable relatively to the platen carriage to reduce the height of the machine when not in use.

9. In a collapsible visible typewriting machine, the combination of upwardly and rearwardly movable type-bars, key-operated means for actuating the type-bars, a platen carriage, and a ribbon guide and platen both shiftable vertically from an elevated operative position relatively to the type-bars to a lower position out of coöperative relation with the type-bars and closer to the type-bars and platen carriage.

10. In a collapsible typewriting machine, the combination of a platen, a carriage bed, a platen carriage having collapsible means for supporting the platen to move toward and from the bed, a ribbon guide, and collapsible means mounted on the bed for supporting the guide to move toward and from the bed.

11. In a collapsible typewriting machine, the combination of a support, type-bars mounted on the support, a platen carriage mounted on the support, a keyboard, a platen, and means whereby the keyboard and platen may be moved from their normal extended positions in coöperative relation with the type-bars to more compact inoper-

ative positions in closer relation with the type-bars and platen carriage to reduce the size of the machine.

12. In a collapsible typewriting machine, 5 the combination of a support, type-bars mounted on the support, a platen carriage mounted on the support, a keyboard, a platen, a ribbon guide, and means whereby said keyboard and the platen and ribbon 10 guide may be moved relatively to the type-bars and carriage from their normal extended operative positions to more compact inoperative positions in closer relation with the type-bars and platen carriage.
13. In a collapsible typewriting machine, 15 the combination of a support, type-bars mounted on the support, a platen carriage mounted on the support, a keyboard, a platen, vertically extensible and collapsible 20 means mounted on the carriage for supporting the platen, a vertically extensible and collapsible ribbon holder mounted on the support, and a support for the keyboard shiftable forwardly and rearwardly relatively to the type bar support to permit the 25 keyboard to be moved toward and from a compact inoperative position in close relation with the type bars.

14. In a collapsible typewriting machine, 30 the combination of type bars, a platen carriage, a platen, a keyboard, and means whereby the keyboard and platen may be shifted relatively to the type bars and platen carriage into compact relation with 35 each other when the machine is not in use.

15. In a collapsible typewriting machine, 40 the combination of type bars, a platen, a platen carriage, a keyboard, and means whereby the keyboard and platen may be shifted relatively to the type bars and carriage and in planes at right angles with each other toward and from a compact inoperative position in close relation with each other and in close relation with the carriage 45 and type bars.

16. In a collapsible typewriting machine, 50 the combination of a support, type bars mounted on said support, a platen carriage mounted on the support, a keyboard, ribbon 55 spools mounted on said support in fixed relation therewith, a ribbon guide mounted on said support, and means whereby the keyboard and platen and said ribbon guide may be shifted relatively to the type bars and carriage from their normal extended operative positions into inoperative positions in closer relation with the type bars and carriage.

17. In a collapsible typewriting machine, 60 the combination of a main frame part, type bars mounted on said frame part, a platen carriage mounted on said frame part, a keyboard frame part slidably held to the main frame part to move into and out of 65 the same, a keyboard supported on the key-

board frame part, a platen, and extensible and collapsible means mounted on the carriage for rotatably supporting the platen at its ends.

18. In a collapsible typewriting machine, 70 the combination of a main frame part, type bars mounted on said frame part, a platen carriage mounted on said frame part, a keyboard frame part slidably held to the main frame part to move into and out of the same, 75 a keyboard supported on the keyboard frame part, a platen, extensible and collapsible means mounted on the carriage for rotatably supporting the platen at its ends, an extensible and collapsible ribbon holder 80 mounted on the main frame, and ribbon spools mounted on the main frame part.

19. In a collapsible typewriting machine, 85 the combination of a main frame part, type bars mounted on said main frame part, a platen carriage mounted on the main frame part, a keyboard frame part slidably held to the main frame part to move into and out of the same, keys supported on the keyboard frame part, collapsible constantly maintained operating connections between the keys and type bars, a platen, and collapsible 90 means mounted on the carriage for rotatably supporting the platen.

20. In a collapsible typewriting machine, 95 the combination of a main frame part, type bars mounted on said main frame part, a platen carriage mounted on the main frame part, a keyboard frame part slidably held to the main frame part to move into and 100 out of the same, keys supported on the keyboard frame part, collapsible constantly maintained operating connections between the keys and type bars, a platen, and collapsible means mounted on the carriage for 105 rotatably supporting the platen, said means being operable to lower the platen vertically into close relation with the upper side of the carriage.

21. In a collapsible visible typewriting 110 machine, the combination of a main frame part, upwardly and rearwardly movable type bars pivotally supported in the main frame part, a keyboard frame part slidably held to the main frame part, keys supported on 115 the keyboard frame part and movable therewith beneath the type bars and within the main frame part, a platen carriage mounted on the main frame part, and collapsible means mounted on the carriage for normally supporting the platen in an elevated 120 position in co-operative relation with the type bars, said means being operable to lower the platen vertically to an inoperative position into close relation with the carriage 125 and keys when the machine is not in use.

22. In a collapsible typewriting machine, 130 the combination of a box-like frame having a main portion and a plurality of foldable portions hinged to said main portion, a hori-

zontally slidable keyboard held to the main portion of the frame and movable into and out of the same, type bars mounted on the main portion of the frame, collapsible operating connections between the keys of the keyboard and the type bars, a platen carriage mounted on the main portion of the frame, a platen, collapsible supporting means for the platen mounted on the carriage, and a collapsible ribbon holder mounted on the main portion of the frame, said box-like frame serving as a support for the parts of the machine when the parts are in extended coöperative relation and being adapted to completely inclose the parts of the machine when the parts are in collapsed position.

23. In a collapsible visible typewriting machine, the combination of a platen carriage, knuckle jointed arms held at their lower ends to the carriage, and a platen rotatably supported at its ends in the upper ends of said knuckle jointed arms.

24. In a collapsible visible typewriting machine, the combination of a platen carriage, a pair of knuckle jointed arms adjacent each end of the carriage and pivotally held at their lower ends thereto, and a platen rotatably supported at its ends in the upper ends of said pairs of arms.

25. In a collapsible typewriting machine, the combination of a platen carriage, a pair of knuckle jointed arms adjacent each end of the platen carriage and pivotally held at their lower ends thereto, and a platen having a shaft journaled in the upper ends of said pairs of jointed arms.

26. In a collapsible typewriting machine, the combination of a platen carriage, a pair of knuckle jointed arms adjacent each end of the platen carriage and pivotally held at their lower ends thereto, a platen having a shaft journaled in the upper end of said pairs of jointed arms, a ribbon guide, and a pair of knuckle jointed arms for supporting said ribbon guide adjacent the printing point.

27. In a typewriting machine, the combination of a frame, ribbon spools mounted on the frame, a platen carriage bed, a ribbon guide, and collapsible means mounted on the bed for supporting said guide, said means embodying a pair of arms having sections foldable relatively to each other to permit movement of the guide from its normal position into more compact relation with the bed and spools.

28. In a compactible typewriting machine, the combination of a ribbon guide, and collapsible means for supporting said guide embodying a pair of arms pivotally connected at their upper ends with the guide and each having sections pivotally connected to fold relatively to each other to permit movement of the guide from its nor-

mal position to a more compact inoperative position when the machine is not in use.

29. In a typewriting machine, the combination of a carriage bed, a bracket held to the bed having a slot therein extending at 70 a right angle to the bed, a pair of arms pivotally connected at their upper ends and having relatively foldable sections, a ribbon guide supported at the upper ends of said arms, a pair of links, means pivotally 75 connecting the outer end of each link with the adjacent ends of the foldable sections of one of said arms, a locking screw extending through said slot in the bracket and pivotally connecting the inner ends of said 80 links, and means for pivotally connecting the lower ends of said arms with the bracket at opposite sides of said slot.

30. The combination of a platen having a shaft, and a traveling collapsible support 85 for the platen comprising a member extending longitudinally of the platen, a pair of brackets projecting at one side of said member adjacent opposite ends thereof and having slots therein, a pair of arms adjacent 90 each end of said member in the upper ends of which the platen shaft is journaled, means for pivotally connecting the lower ends of each pair of arms to said member adjacent opposite edges thereof, each of said arms 95 having two relatively foldable sections, a pair of links connecting each pair of arms, means for pivotally connecting the outer end of each link and the adjacent ends of the sections of one arm, and locking screws 100 extending through the slots in the brackets and pivotally connecting the inner ends of each pair of links.

31. The combination of a platen having a shaft, and a platen carriage having means 105 adjacent each end thereof in which the platen shaft is journaled, said means being collapsible to permit shifting of the platen from a normal position spaced from the base of the carriage to a more compact position closer to the base of the carriage.

32. In a collapsible visible typewriting machine, the combination of a frame, type bars pivotally supported in the frame to move upwardly and rearwardly to the printing point, key-operated means for actuating the type bars, a carriage bed supported in the frame closely adjacent the type bar pivots, a platen, and a platen carriage mounted on said bed having vertically collapsible 115 means adjacent its ends for normally supporting the platen in an elevated position in coöperative relation with the type-bars.

33. In a collapsible typewriting machine, the combination of a main frame part having a closed bottom and a rear wall and side walls, normally substantially horizontally disposed type bars mounted within the main frame part, a key-board frame part movable rectilinearly into and out of the 125 130

- main frame part, keys movable with the keyboard frame part into and out of the main frame part, a platen, a vertically collapsible traveling support for the platen 5 mounted on the main frame part, ribbon spools mounted on the main frame part, and a plurality of plates hinged to the main frame part to form together with said frame part a box-like case adapted to inclose all 10 parts of the machine when the keyboard frame part is moved into the main frame part and the traveling platen support is collapsed.
34. In a collapsible typewriting machine, 15 the combination of a main frame part having a closed bottom and a rear wall and side walls, normally substantially horizontally disposed type bars mounted within the main frame part, a key-board frame part 20 movable rectilinearly into and out of the main frame part, keys movable with the keyboard frame part into and out of the main frame part, a platen, a vertically collapsible traveling support for the platen 25 mounted on the main frame part, ribbon spools mounted on the main frame part, and a plurality of plates hinged to the main frame part to form together with said frame
- part a box-like case adapted to inclose all parts of the machine when the keyboard 30 frame part is moved into the main frame part and the traveling platen support is collapsed, one of said plates being hinged to the forward edge of the bottom of the main frame part and adapted to support the keyboard frame part when the keyboard frame part is in its extended position.
35. In a typewriting machine, the combination of a frame, upwardly and rearwardly movable type-bars pivotally supported in the frame, keys operatively connected to operate the type-bars, a platen, traveling platen-carrying means, and stationary means on the frame for supporting the platen-carrying means, said platen-carrying means being foldable to permit movement of the platen relatively to said stationary supporting means from a normal position above and at the rear of the type-bars to a compact lower position in substantially the same vertical plane and out of co-operative relation with the type-bars.

This specification signed this twelfth day of January, A. D. 1918.

PHILIPPE DE CLAMECY.
